US0D1043341S

(12) **United States Design Patent** (10) Patent No.: **US D1,043,341 S**
(45) Date of Patent: ** Sep. 24, 2024

(54) **CLOSURE**

- (71) Applicant: **The Procter & Gamble Company**,
Cincinnati, OH (US)
- (72) Inventors: **Mauro Alvarado, Jr.**, Cincinnati, OH
(US); **Raymond Charles Bell**,
Cincinnati, OH (US)
- (73) Assignee: **The Procter & Gamble Company**,
Cincinnati, OH (US)

(**) Term: **15 Years**

(21) Appl. No.: **29/803,044**

(22) Filed: **Aug. 10, 2021**

(51) LOC (14) Cl. **09-07**

(52) U.S. Cl.

USPC **D9/453; D9/454**

CLAIM

The ornamental design for a closure, as shown and described.

DESCRIPTION

FIG. 1 is a perspective view of a closure;

FIG. 2 is a front view thereof;

FIG. 3 is a side view thereof;

FIG. 4 is a rear view thereof;

FIG. 5 is a side view thereof, opposite the side view of FIG. 3;

FIG. 6 is a top view thereof; and,

FIG. 7 is a bottom view thereof.

The broken lines shown illustrate portions of the closure and form no part of the claimed design.

1 Claim, 4 Drawing Sheets
